JET PROPULSION APPARATUS

Henry J. De N. McCollum, deceased, late of Chicago, Ill., by Thelma McCollum, executrix, Chicago, Ill., assignor to Stewart-Warner Corporation, Chicago, Ill., a corporation of Virginia

Application March 23, 1945, Serial No. 584,362

8 Claims. (Cl. 170—135.4)

1

The present invention relates to jet propulsion apparatus and more particularly to jet propelled aircraft.

One of the primary objects of the present invention is to provide a new and improved jet propulsion type aircraft wherein the reaction of a jet is utilized to rotate an airplane propeller thereby to provide a more efficient slow speed airplane.

Another object of the present invention is to provide jet propelled aircraft requiring but little apparatus and which may be used in connection with a variable pitch propeller.

A further object of the present invention is to provide a new and improved jet propulsion apparatus wherein the jet reaction drives a propeller and wherein the propeller in turn is utilized to drive a fuel pump.

Still another object of the present invention is to provide a new and improved jet propelled propeller driven aircraft having new and improved means for supplying a combustible mixture to jet producing means mounted at the tips of the propeller blades and which, more specifically, includes means for supplying combustion air by aspiration and wherein the air is aspirated by vaporized fuel at high pressure, thereby to minimize the amount of apparatus necessary and to increase the efficiency of the apparatus.

Other objects and advantages of the present invention will become more apparent from the ensuing description, in the course of which reference is had to the accompanying drawings, in which

Fig. 1 is a somewhat diagrammatic and mainly cross-sectional view through jet propulsion apparatus constructed in accordance with the present invention;

Fig. 2 is a fragmentary reduced scale perspective view, partly in section, of the variable pitch propeller of Fig. 1 and the jet producing means mounted at the tip of the propeller;

Fig. 3 is a fragmentary enlarged axial view through the jet producing means mounted at the tip of a propeller blade;

Fig. 4 is a fragmentary cross-sectional view of the jet producing means taken along the line 4—4 of Fig. 3;

Fig. 5 is a vertical axial cross-sectional view through fuel vaporizing means illustrated also in Fig. 1; and

Fig. 6 is an enlarged fragmentary detail of the fuel and air injecting means for the fuel vaporizer.

The present invention is in the nature of an improvement over the inventions disclosed and claimed in the copending application, Serial No.

2

587,927, filed April 12, 1945, now abandoned, and Patent No. 2,502,332, issued March 28, 1950. In these applications there is disclosed jet propulsion apparatus having no power loss resulting from the furnishing of compressed air, as by a compressor, and operating at a lower temperature. The apparatus includes a fuel vaporizer for supplying vaporized fuel at high temperature and pressure to a jet entraining and aspirating air necessary for combustion. A portion of the heat of the products of combustion is used to vaporize the fuel. Accordingly, the apparatus operates at lower temperatures and requires no compressor.

15 The apparatus of the present invention includes a fuel vaporizer of the character described and it is utilized to supply a combustible mixture to jet producing means mounted at the tips of propellers, thereby to provide a simplified and more 20 efficient slow speed propeller driven airplane.

25 Referring now to the drawings and mainly to Figs. 1 and 2, the jet propulsion apparatus is housed within a housing or nacelle 10 which is secured in conventional fashion to or made part 30 of an airplane (not shown). A variable pitch propeller having hollow blades 12 is mounted in front of the nacelle and a housing 14 having a rounded closed front end is secured in front of the propeller. A streamlined construction is provided by housings 10 and 14 and a connecting housing 16 surrounding the inner portions of the propeller blades.

35 The propellers are rotated by jet producing means 18 mounted at the tips of the blades constructed and arranged to produce jets that are tangentially disposed relative to the blade tips. The jet producing means, which will be described in greater detail shortly, are, in substance, combustion chambers in which a combustible mixture is burned to provide high temperature and 40 high pressure combustion products which escape to atmosphere through nozzles, whereby the propeller is rotated by the reaction of the jet.

45 The combustible mixture of air and fuel is produced by injecting vaporized fuel at high temperature and pressure into an injection tube and utilizing the fuel jet to entrain and aspirate the air necessary for combustion. The fuel is vaporized by a vaporizer indicated as a whole by reference character 20 having a fuel outlet connection 22 leading to a nozzle 24 disposed axially of a Venturi tube like mixing tube 26 fixedly secured to the propeller blade supporting means. The nozzle is located near the throat 28 of the tube, which has an enlarged trailing end 30 through which air is led to the tube.

Air is supplied to the mixing tube from atmosphere by a conduit 32 having a reverse bend in it and projecting beyond the front of the housing 10, which is provided with an aperture 34 for the conduit. In normal operation during flight, the air will thus be at a relatively high pressure.

The combustible mixture is supplied to the jet producing means 18 at the tips of the blades by conduits 36 extending through and fixedly secured to move with the blades. The inner ends of the blades are located adjacent the outer ends of the branch conduits 38 at the front end of the mixing tube 28, the construction thus being such that propeller blades may be moved for pitch adjustment without in any way affecting the supply of combustible mixture to the jet producing means.

The fuel vaporizer 20, which is preferably located above the mixing tube is supplied with vaporized high pressure and temperature fuel during normal operation through a branch conduit 40 terminating in a nozzle 42 axially disposed near the throat 44 of a Venturi-like mixing tube 46. In starting, a highly volatile fuel, such as propane, is supplied to the mixing tube through a second nozzle 48. It injects air at a low pressure so that there is provided a combustible mixture which will vaporize the fuel. In order to conserve heat the fuel connections 22 and 40 are covered by a heat insulating jacket 50.

Air is supplied to the fuel vaporizer through a conduit 52 leading from the mixing tube 46 to the air inlet conduit 32.

The combustible mixture is supplied to an ignition chamber 54 and thence to a combustion chamber 56 from which it is exhausted, as to atmosphere, through an exhaust pipe 58. The mixture in chamber 54 is ignited, at least initially, by an electrical igniter 60 secured to the chamber casing and supplied with current through conductor 61.

The fuel is vaporized by the hot products of combustion in chamber 56. It is preferred that the fuel be vaporized in a coil 62 located near the chamber wall, although other arrangements can be used. The fuel, which may be gasoline, is supplied to the coil from suitable source through a high pressure fuel line 64 leading to a pressure control valve 66.

The pressure control valve is preferably of a type fully described in the previously referred to copending applications. In the instant case, however, it is adapted to be connected selectively to two different sources of fuel under pressure rather than to one. It is connected to a source of gasoline (not shown but which may be a tank in the aircraft) through a conduit 68, a fuel pump 70, conduit 72 and an inlet fitting 74 attached to the lower end of the valve 66. The pump 70 is, in accordance with one of the features of the present invention, driven by the propeller through gearing indicated generally by reference character 76 and which will be described in complete detail hereinafter. In order to provide regulated quantities of fuel to the pump, the pressure control valve 66 is adapted to by-pass any undesired excess of liquid fuel back to the tank as through a relief passage defining conduit 77. Any leakage past the valve member (not shown) is returned to the tank through a second return conduit 78. Adjustment of the pressure at which the control valve operates is effected through a suitable control actuatable through a rod 80.

In order that fuel may be supplied to the apparatus when the propeller is not rotating, there is provided a second source including a fuel pump 82 which is driven as by an electric motor 84 supplied with energy, when desired, through a conductor 86. The inlet side of the pump is connected to the fuel supply line 68 by a branch conduit 88 and to the valve fitting 74 through a conduit 90. Suitable means such as a spring-pressed ball valve 92 are provided to prevent a back flow of liquid through the motor driven pump 82 when the main fuel pump 70 is driven by the propeller.

As heretofore indicated, the main fuel pump 70 is driven by the propeller which is rotated by the jet propulsion apparatus. The fuel pump is driven through the previously referred to gearing 76 and a tubular sleeve-like extension 94 of the main propeller blade supporting structure 96. The tubular extension 94 thus rotates with the propeller and with the mixing tube 26 which extends through and is secured to it. The rear end of the mixing tube 26 is preferably supported within the tubular extension by a spider 98, while the forward end of the tube is supported in the propeller blade supporting structure.

The fuel pump 70 is secured to the main supporting structure 100 which is suitably secured to the aircraft. The pump shaft 102 is connected to the tubular extension 94 through gears 104, 106 and 108, the first of which is on the pump shaft and the last of which is on the sleeve 94. Thus, as the sleeve is rotated by the propeller, the pump is also rotated.

The tubular extension 94 and the propeller supporting structure 96, which are preferably formed integral, are supported in the main supporting structure 100. The supporting means includes a front bearing 110, a rear thrust bearing 112, and an intermediate roller bearing 114. Rotary lubricant seals 116 and 118 are located at the front and rear ends of the supporting structure and a third seal 120 is located intermediate the ends and closely adjacent the thrust bearing 112.

The rear end of the tubular extension extends beyond the supporting structure and has mounted on it a pair of insulated slip rings 122 and 124, the former of which is connected by conductor 126 to an electric motor 128 constituting part of the mechanism controlling the pitch of the propeller. The motor is operatively connected to bevel gears 130 and 132 fixedly connected to the inner ends of the propeller blades 12 by gearing indicated generally by reference character 134 and including a bevel gear 136 meshing with the bevel gears 130 and 132. The pitch control mechanism may be of various types, that illustrated being a Curtiss electric propeller of a type well known to those skilled in the art so that it need not be described in detail. The second slip ring 124 is connected by conductor 138 and branch conductors 140 and 142 to ignition means forming part of the jet producing means 18 at the propeller tips.

The jet producing means of the present invention is best illustrated in Figs. 2, 3 and 4 to which reference is now had. Each jet producing means includes a generally cylindrical ignition chamber 144 to which the combustible mixture supplying conduits 36 are connected and opening into a generally conical combustion chamber 146 having a nozzle defining escape opening 148 of small diameter at its trailing end. A streamlined configuration is given to the jet producing means by the shape of the combustion chamber and a gen-

erally rounded end cap 150 suitably secured as by welding to the combustion chamber and to the tip of the hollow propeller blade 12. The combustion chamber 146 is also secured to the propeller tip.

The combustible mixture supplied to the jet propulsion means is ignited by an electrical igniter 152 secured to the ignition chamber 144.

It is believed that the operation of the apparatus of the present invention will be fairly apparent from the foregoing detailed description thereof but a brief review of the operation as a whole will be made. In order to start the apparatus, the fuel vaporizer is first brought to a high temperature using the auxiliary source of fuel, which may be propane or butane supplied through the nozzle 48. This is readily accomplished by suitable fuel control means such as a valve which may be opened to supply the fuel to the vaporizer 20. At the same time the igniter 60 is supplied with electric current. The fuel injects air at relatively low pressure, the air flowing through the conduits 32 and 52. The mixture is burned in the ignition and combustion chambers 54 and 56 of the vaporizer until the vaporizer is hot.

After the vaporizer has been brought up to a high temperature, the electric motor driven fuel pump 82 is placed into operation. It pumps fuel to the vaporizer through the conduit 64, the heat exchanger coil 62 within the vaporizer. The gasoline is vaporized and the pressure gradually built up until the mixture supplied to the jet producing means 18 through the mixing tube 26 and the conduits 36 in the propeller blades starts to burn and the propeller starts turning. Some of this fuel is also supplied to the vaporizer 20 through the nozzle 42.

The auxiliary fuel is shut off as soon as the vaporizer is hot enough to vaporize gasoline in sufficient quantity to keep the system in operation. Once the propeller starts turning, the auxiliary fuel pump can also be cut off because the main fuel pump 70, which is driven by the propeller, is effective to supply sufficient fuel to the vaporizer through the pressure control valve 66. Excess liquid fuel is returned to the storage tank through the by-pass conduit 76.

The apparatus of the present invention has many advantages. It is light in construction because it does not require any multiple stage air compressor and it operates at low temperatures. It can be constructed as a compact and simple unit which can be manufactured readily and economically and which constitutes a simple replaceable unit.

Having thus described the invention, what is claimed to be new and desired to be secured by Letters Patent is as follows:

1. Jet propelled aircraft, including in combination, a rotatable propeller having blades and combustion chamber jet producing means at the propeller blade tips, means including a mixing tube having an air intake and means supplying said mixing tube with vaporized fuel at a high pressure and a high temperature whereby air is mixed with the fuel by aspiration for supplying a combustible mixture, and means for conducting the combustible mixture to the combustion chamber jet producing means at said blade tips.

2. Jet propelled aircraft, including in combination, a rotatable propeller having blades and combustion chamber jet producing means at the propeller blade tips, means including a mixing tube rotated with the propeller having an air intake and stationary fuel injecting means ex-

tending into said tube through said air intake for supplying a combustible mixture of air and fuel, and means for conducting the combustible mixture from the tube to the combustion chamber jet producing means at said blade tips.

3. Jet propelled aircraft, including in combination, a propeller having blades and jet producing means at the blade tips, a mixing tube having an air intake and a discharge end, conduit means connecting said air intake to a point at the leading edge of the aircraft, conduit means connecting the discharge end of said tube to the jet producing means, means for supplying and injecting high pressure and high temperature vaporized fuel to said tube thereby to entrain and aspirate air with the fuel to produce a combustible mixture, said last mentioned means including a fuel vaporizer, a second mixing tube having an air intake and discharge end, means connecting the discharge end to said vaporizer, conduit means connecting the air intake of the last mentioned tube to first mentioned conduit means, and means for supplying fuel and injecting the fuel into said last mentioned tube near said air intake to produce a combustible mixture for said vaporizer.

4. Jet propelled aircraft, including in combination, a propeller having blades and jet producing means at the blade tips, a mixing tube having an air intake and a discharge end, conduit means connecting said air intake to a point at the leading edge of the aircraft, conduit means connecting the discharge end of said tube to the jet producing means, means for supplying and injecting high pressure and high temperature vaporized fuel to said tube thereby to entrain and aspirate air with the fuel to produce a combustible mixture, said last mentioned means including a fuel vaporizer, a conduit conducting the fuel through the vaporizer, a second mixing tube having an air intake and discharge end, means connecting the discharge end to said vaporizer, conduit means connecting the air intake of the last mentioned tube to first mentioned conduit means, and means including said fuel conducting conduit for supplying fuel and injecting the fuel into said last mentioned tube near said air intake to produce a combustible mixture for said vaporizer.

5. Jet propelled aircraft, including in combination, a propeller having blades and jet producing means at the blade tips, a mixing tube having an air intake and a discharge end, conduit means connecting said air intake to a point at the leading edge of the aircraft, conduit means connecting said discharge end of said tube to the jet producing means, means for supplying and injecting high pressure and high temperature vaporized fuel to said tube thereby to entrain and aspirate air with the fuel to produce a combustible mixture, said last mentioned means including a fuel vaporizer, means including a pump and conduit passing through the vaporizer for supplying said fuel, a second mixing tube having an air intake and discharge end, means connecting the discharge end connected to said vaporizer, conduit means connecting the air intake of the last mentioned tube to first mentioned conduit means, means including said fuel supplying conduit for supplying fuel and injecting the fuel into said last mentioned tube near said air intake to produce a combustible mixture for said vaporizer, and means for supplying fuel from another source and injecting it into said second mentioned tube.

6. Jet propelled aircraft, including in combi-

nation, a propeller having blades and jet producing means at the blade tips, means including a pair of fuel pumps for supplying said jet producing means with a combustible mixture, propeller actuated means for driving one of said fuel pumps, and means including a selectively operable motor for driving the other of said pumps.

7. Jet propelled aircraft, including in combination, a propeller having blades and jet producing means at the blade tips, means including a pair of fuel pumps and a pressure control valve connected to the discharge sides of both pumps for supplying said jet producing means with a combustible mixture, propeller actuated means for driving one of said fuel pumps, and means including a selectively operable electric motor for driving the other pump.

8. An aircraft power plant comprising in combination a rotatable propeller and jet producing means at the propeller tips, means connected to said jet producing means for supplying combustible mixture thereto including a mixing and velocity recovery tube having an air intake, injector nozzle means associated with said intake, a source of liquid fuel supply, pump means for raising said fuel to a high pressure, a boiler connected to receive fuel from said pump means and for converting said liquid fuel under high pressure to the vapor phase, and means for conducting said vaporized fuel at high pressure to said injector nozzle means so that vaporized fuel issuing at high velocity from said nozzle means

will entrain air to form a combustible mixture stream in said mixing tube wherein the high velocity of said mixture stream will be recovered as pressure so that mixture is supplied to said jet producing means in a compressed state.

THELMA McCOLLUM,
*Executrix of the Last Will and Testament of
Henry J. De N. McCollum, Deceased.*
